[57] CLAIM

A new and ornamental design for seat, as shown and described above.

DESCRIPTION

FIG. 1 is a left side elevational view of a seat showing my new design, the opposite side being a mirror image; FIG. 2 is a front elevational view;

FIG. 3 is a top plan view;

FIG. 4 is a bottom plan view;

FIG. 5 is a rear elevational view thereof;

FIG. 6 is a left side elevational view of my second embodiment of my new design of FIGS. 1-5, the opposite side being a mirror image;

FIG. 7 is a front elevational view;

FIG. 8 is a top plan view;

FIG. 9 is a bottom plan view;

FIG. 10 is a rear elevational view thereof;

FIG. 11 is a left side elevational view of a third embodiment of my new design of FIGS. 1-5 the opposite side being a mirror image;

FIG. 12 is a front elevational view;

FIG. 13 is a top plan view;

FIG. 14 is a bottom plan view;

FIG. 15 is a rear elevational view thereof;

FIG. 16 is a front elevational view of a fourth embodiment of my design of FIGS. 1-5;

FIG. 17 is a left side elevational view the opposite side being a mirror image;

FIG. 18 is a top plan view;

FIG. 19 is a bottom plan view;

FIG. 20 is a rear elevational view thereof.

The broken lines in the drawing are understood to be for illustrative purposes only showing environmental structure in which the claimed design of the present invention can be employed.
